UNITED STATES PATENT OFFICE.

WILBUR L. SWIFT, OF NEW YORK, N. Y., ASSIGNOR TO THE UNION SPECIAL SEWING MACHINE COMPANY, OF CHICAGO, ILLINOIS, A CORPORATION OF ILLINOIS.

FOLDING AND TAPING GUIDE FOR SEWING-MACHINES.

No. 889,063.

Specification of Letters Patent.

Patented May 26, 1908.

Application filed September 1, 1899. Serial No. 729,167.

To all whom it may concern:

Be it known that I, WILBUR L. SWIFT, a citizen of the United States, residing at New York, in the county of New York, State of New York, have invented certain new and useful Improvements in Folding and Taping Guides for Sewing-Machines, of which the following is a description, reference being had to the accompanying drawing, and to the letters and figures of reference marked thereon.

My invention relates to an improvement in sewing machines, of the type known as the Union Special Yoke Ruffling Machine, such as illustrated in an application filed by R. G. Woodward, July 20, 1898, Serial No. 686,444 patented July 31, 1900, No. 655,143, to which patent, reference is made for understanding of the operation of the ruffling mechanism.

The present invention comprises a sewing machine having suitable stitch forming mechanism and a ruffling mechanism with means for guiding the edge of the fabric to be ruffled and of the fabric to which the ruffled portion is to be secured to the stitch forming mechanism with means for covering or binding the raw edge of the ruffled piece, this means for covering the raw edge being herein shown as a tape, whereby said rough edge of the fabric to be ruffled may be covered and the folding, guiding, ruffling, sewing and covering of the seam being all accomplished in a continuous operation.

Furthermore, the invention comprises a folding guide especially constructed for this machine.

The invention is illustrated in the accompanying drawings, in which

Figure 1 is a perspective view of a portion of a union special yoke ruffling machine, showing my invention applied thereto; Fig. 2 is a top plan view of my improved folding guide and tape guide; Fig. 3 is an end view of the same; and Fig. 4 is a top plan view partly broken away, showing the work accomplished by the use of this invention.

In these drawings, the needle lever A, gooseneck B, ruffling mechanism C, cloth plate D, needle bar E, presser bar F, presser foot G, needle a, and other parts are similar to those illustrated in the aforesaid application.

H represents a plate secured to the cloth plate of the machine and having a raised portion b with a downwardly sloping part c to which is attached as shown in Fig. 2 by

set screws the stripper plate or blade d, which extends forward to a point in proximity to the needle. Attached to or formed with this part c is the folding guide part, having the bottom walls f, the upwardly turned wall g, the horizontal wall h, the upwardly turned wall i, and the lip j. Projecting upwardly from the horizontal wall h is the wall m, having the horizontal parts k which are provided with a downwardly turned portion l, which is adapted to press the materials to be sewed together firmly just as they pass under the action of the presser foot. Removably attached to the plate H is a plate n which is formed with or carries the tape guide o.

In operation, the edge of the piece of fabric to be ruffled is laid in the guiding recess formed by the walls f, g, and h, the edge of the upper piece of fabric is folded in and guided by the walls m, k, i, j, and h, and the tape is fed through the slot o, which in Fig. 1 is shown as closed, while in Fig. 3 the lower wall of said tape slot is separated. As the feed of the sewing machine progresses the parts are all fed to the sewing mechanism, the upper piece of fabric folded and overlapped with the single thickness which is ruffled and the parts united and the seam taped, all in one operation.

In Fig. 4, 1 represents the upper fabric, 2 the tape and 3 the piece which is ruffled and its raw edge covered by the tape.

Various minor modifications and changes may be made without departing from the spirit of my invention.

Having thus described my invention, what I claim and desire to secure by Letters Patent, is:

1. The herein described folding guide for sewing machines, comprising a base piece adapted to be secured to the work plate of the sewing machine having a raised portion, a folding guide portion secured to said raised portion and having a bottom wall, a vertical wall and an upper horizontal wall forming a recess to receive the edge of a fabric, a second upwardly turned wall, a lip as j, a vertical wall m having the oppositely extending horizontal portion k, below the lip, and a tape guide below the folding guide attached to said base piece adjacent the raised portion; substantially as described.

2. The herein described folding guide for sewing machines, comprising a base piece

adapted to be secured to the work plate of the sewing machine having a raised portion, a folding guide portion secured to said raised portion and having a bottom wall, a vertical wall, and an upper horizontal wall forming a recess to receive the edge of a fabric, a second upwardly turned wall, a lip as *j*, a vertical wall *m* having the oppositely extending horizontal portion *l*, below the lip, and having at 10 the forward end a downwardly turned tongue as *l*; and a tape guide attached to said base piece adjacent the raised portion and below the folding guide substantially as described.

3.. The herein described folding and guiding attachment for ruffling and sewing machines, comprising a ruffling device and means for operating it, a base piece adapted 15

to be attached to the sewing machine and having a raised portion, a stripper plate secured to said raised portion, and a folding 20 guide having recesses arranged one above the other and opposed to each other, the lower of said recesses being arranged in a plane with the top of the stripper blade over which one layer of the goods to be sewed passes, and a 25 tape guide arranged below said recess and attached to the base piece; adjacent the raised portion substantially as described.

In testimony whereof I affix my signature, in presence of two witnesses.

WILBUR L. SWIFT.
